UNITED STATES PATENT OFFICE.

CASPER JAMES REASONER, OF DOWS, IOWA, ASSIGNOR OF ONE-THIRD TO ARMIE LANGE, OF HIGHMORE, SOUTH DAKOTA.

AUTOMATIC WAGON BRAKE.

Application filed September 23, 1922. Serial No. 590,027.

To all whom it may concern:

Be it known that I, CASPER J. REASONER, a citizen of the United States, residing at Dows, in the county of Wright and State 5 of Iowa, have invented new and useful Improvements in Automatic Wagon Brakes, of which the following is a specification.

The object of my said invention is the provision of a wagon brake embodying a 10 simple, durable and efficient means for utilizing the tendency of the load to move forwardly and downwardly when a wagon is descending a hill to apply the brakes, the application of the brakes being in proportion to the degree of the grade, and being therefore calculated to properly retard a vehicle incident to the descent of a hill.

To the attainment of the foregoing, the invention consists in the improvement as 20 hereinafter described and definitely claimed.

In the accompanying drawings, forming part of this specification:—

Figure 1 is a longitudinal vertical section of a wagon embodying my invention. 25 Figure 2 is a plan view of the same with the body removed.

Figure 3 is an inverted plan view of the body.

Figure 4 is an enlarged detail view showing the manner in which the transverse rollers are mounted on the bolsters of the wagon.

Similar numerals of reference designate corresponding parts in all of the views of 35 the drawings.

The wagon body is designated by 1, and in accordance with my invention is provided at its underside with a forward wear plate 2 and with a rear wear plate 3, the said 40 plate 3 being flanged as indicated by 4. Both of the said plates 2 and 3 are fixed to the body and are disposed transversely thereof. The body 1 is also provided on its bottom and at a point in rear of the 45 plate 2 with a connecting member 5, Figures 1 and 3.

In accordance with my invention transverse rollers 6 are arranged above the bolsters 7 of the running gear of the wagon. 50 The said rollers 6 may be mounted to freely turn above the bolsters in any manner compatible with the purpose of my invention. I prefer, however, to provide the rollers 6 at their ends with reduced journals 8, 55 Figures 2 and 4, and I also prefer to ar-

range the said journals 8 within circular series of anti-friction rollers 9, carried in housings 10 superimposed upon and appropriately fixed to the bolsters.

Also in accordance with my invention I 60 mount brake levers 11 on a transverse beam 12, fixed on the running gear frame 13 of the wagon. The said levers 11 are provided at their outer ends with shoes 14 arranged in opposed relation to the rear wheels 15 65 of the wagon. The inner arms of the levers 11 are connected through the medium of the links 16 with a longitudinal rod 17, and the said rod 17 is connected at its forward end to the member 5 carried as before stated by the body 1.

In virtue of the construction described, it will be manifest that when the wagon is descending a grade, the body 1 will move forwardly and downwardly and by so doing will rock the levers 11 and apply the shoes 14 to the wheels 15 and thereby retard the movement of the wagon. It will also be manifest that the downward movement of the body 1 will be limited by the application of the shoes 14 to the peripheries of the wheels 15, and that the brakes will be applied in proportion to the load in or on the body 1 and the tendency of the said load to move with the body 1 forwardly and 75 downwardly.

As best shown in Figure 1 the body 1 is slightly inclined from the horizontal, the forward end of the body being higher than the rear end thereof. From this it follows 90 that when the wagon is transversing a level road, the body whether loaded or unloaded will tend to assume the relative position shown in Figure 1, with the result that the brakes will be released and will be 95 maintained in released position. Manifestly the forward flange of the plate 3 will operate to limit the rearward movement of the body 1.

Notwithstanding the capacity of function 100 and the practical advantage hereinbefore ascribed to my improvement, it will be observed that the improvement is simple and inexpensive and therefore is not likely to greatly increase the cost of a wagon.

I have entered into a detailed description of the construction and relative arrangement of the parts embraced in the present and preferred embodiment of the invention in order 105 to impart a full, clear and exact under- 110

standing of the said embodiment. I do not desire, however, to be understood as confining myself to the said specific construction and relative arrangement of parts inasmuch as in the future practice of the invention various changes and modifications may be made such as fall within the scope of my invention as defined in my appended claim.

10 Having described my invention, what I claim and desire to secure by Letters-Patent, is:—

The combination in an automatic wagon brake, of a wheeled frame including bolsters, transverse anti-friction rollers arranged above and alined with the bolsters and having reduced journals at their ends, housings on the bolsters and receiving the said journals of the rollers, anti-friction 15 means disposed in the housings and surrounding the journals of the rollers; the

forward transverse roller being located in a horizontal plane above that of the rear transverse roller, a body arranged in inclined position above the rollers and having plates secured to the bottom thereof and bearing on said rollers, the rear plate having pendent flanges at its forward and rear edges, transverse levers fulcrumed on the wheeled frame and having their outer ends 20 equipped with brake shoes disposed in front of the rear wagon wheels, and a connection between the inner ends of said levers and the bottom of the body at the rear edge of the forward plate, whereby when the body moves forwardly the brake shoes will be applied to the rear wheels in opposed relation thereto.

25 In testimony whereof, I affix my signature.

CASPER JAMES REASONER.
